UNITED STATES PATENT OFFICE.

WILLIAM NOLAN AND CHARLES H. PEARCE, OF ASPEN, COLORADO,
ASSIGNORS OF ONE-HALF TO SAID NOLAN, ONE-FOURTH TO SAID
PEARCE, AND ONE-FOURTH TO FREDRICK R. LEAVER, OF ASPEN,
COLORADO.

RAIL-JOINT.

No. 832,997.

Specification of Letters Patent.

Patented Oct. 9, 1906.

Application filed June 21, 1906. Serial No. 322,770.

To all whom it may concern:

Be it known that we, WILLIAM NOLAN and CHARLES H. PEARCE, citizens of the United States, and residents of Aspen, in the county 5 of Pitkin and State of Colorado, have invented certain new and useful Improvements in Rail-Joints, of which the following is a specification.

Our invention is an improvement in rail-joints; and it consists in certain novel constructions and combinations of parts, as will be hereinafter described and claimed.

In the drawings, Figure 1 is a perspective view of a joint embodying our invention. Fig. 2 is a detail perspective view of the under side of the tie-plate. Fig. 3 is a cross-section of the tie and tie-plate, showing the side and intermediate ribs in the tie-plate seated in the grooves in the tie. Fig. 4 is a 20 transverse section of the rail and the joint, showing the angle-bar secured by the brace and by the abutment of its outer edge against the shoulder of the tie-plate.

In carrying out our invention the tie-plate 25 A is provided on its under side adjacent to one end with depending ribs A' A' near its opposite edges and with an intermediate rib A² extending in a direction transversely to the direction of the rail and seated in use in 30 grooves or recesses B', formed in the upper face of the tie B to aid in anchoring the tie-plate securely to the tie. On its upper side the tie-plate is provided with the brace C, integral with the tie-plate and projecting upwardly toward its end C', where it is adapted 35 at C² to rest beneath the ball D' of the rail D, the upper edge C² of the brace being so related to the inner upright face C³ thereof as to permit the fitting of the upright wing E' of 40 the fish-plate E between the inner end of the brace C and the web D² of the rail D, as shown in the drawings. The brace C at its inner end projects above the tie-plate to permit the lateral wing E² of the fish-plate to fit beneath 45 the brace and to abut at its outer end against a shoulder a on the tie-plate, said shoulder preferably extending from edge to edge of the tie-plate and the tie-plate being stepped to also provide in advance of the shoulder a a 50 shoulder a', against which the edge of the rail-base may bear, as best shown in Fig. 4 of the drawings.

By the described construction it will be

noticed the lateral wing of the fish-plate underlies the inner end of the brace and also 55 abuts at its outer edge against the shoulder a of the tie-plate and is braced thereby on opposite sides of the brace, as well as beneath the brace, in the operation of the device.

The tie-plate may be spiked down or otherwise secured to the tie, as may be desired.

We claim—

1. The combination substantially as herein described of the tie provided in its upper face with longitudinal channels or grooves extending in a direction at right angles to the direction of the rail applied to said tie, the tie-plate secured on said tie and having depending ribs entering the grooves of the tie, the said tie-plate being provided on its upper side 70 with an upwardly-projecting brace to bear beneath the ball of the rail and also provided beneath the outer end of said brace with a shoulder for abutment by the lateral wing of the fish-plate and with a second shoulder for 75 abutment by the edge of a rail-base, the rail having its base abutting against its respective shoulder of the tie-plate and having its ball arranged in position to be supported by the brace, and the fish-plate having its upright wing fitted between the inner end of the brace and the web of the rail and its lateral wing extending outwardly beneath the brace and abutting at its outer edge the shoulder on the tie-plate, substantially as set forth. 85

2. The combination with the rail and fish-plate having an upright wing fitting the web of the rail and the lateral wing extending outwardly beyond the outer edge of the rail-base, and a tie-plate having its upper face 90 stepped providing a shoulder for abutment by the edge of the rail-base, and a second shoulder for abutment by the outer edge of the lateral wing of the fish-plate and also provided with a rail-brace extending inwardly 95 over the said shoulders and adapted to support the ball of the rail, substantially as set forth.

3. A tie-plate for rail-joints provided upon its upper face with a shoulder for abutment by the lateral wing of the fish-plate and having a rail-brace projecting inwardly over said shoulder, combined with a feed-plate having its lateral wing extending outwardly and abutting against the said shoulder, and the 105 rail having its base underlying the said lat-

eral wing of the fish-plate, substantially as set forth.

4. A tie-plate for rail-joints stepped on its upper side forming shoulders for engagement by a fish-plate and a rail-base and having a rail-brace projecting inwardly over said shoulders, substantially as set forth.

5. A tie-plate for rail-joints provided on its under side with longitudinal ribs to seat in grooves in a tie and having upon its upper side laterally-facing shoulders for engagement by a rail-base, and a fish-plate and a rail-brace extending over said shoulders, substantially as set forth.

6. The combination with a rail and a fish-plate having an upright wing fitting to the web of the rail, and a lateral wing extending outwardly beyond the base of the rail, of the tie-plate stepped on its upper side forming shoulders for abutment by the outer edges of said lateral wing, and rail-base, and provided with a brace extending over the said shoulders, substantially as set forth.

WILLIAM NOLAN.
CHARLES H. PEARCE.
